JESSUP SALISBURY, OF HAMDEN, CONNECTICUT, ASSIGNOR TO THE AMERICAN BUCKLE COMPANY, OF WEST HAVEN, CONNECTICUT, A CORPORATION OF CONNECTICUT

LOOP SLIDE BUCKLE

Application filed July 26, 1930. Serial No. 470,932.

This invention relates to loop slide buckles, strap mountings combining an expandable button loop with a slide buckle adapted to be adjustably mounted upon a strap, the button loop being suspended from the slide buckle for a connective engagement with a button provided by a garment thus supported by the strap.

The objects of the invention are to provide an adjustable strap mounting combining a button loop and a slide buckle in which combination a downward pulling strain upon the button loop tightens the grip of the slide buckle upon the strap upon which the device is adjustably mounted; to provide relatively superimposed and pivotally assembled buckle frame members the side bars of which are relatively secured by looped engagements of the button loop; to provide one of the buckle frame members with means for the substantial relative pivotal movement of the frame members while relatively secured by the looped engagements of the button loop; and to provide the gripping portions of the buckle frame members with a strap holding means augmenting the grip of the members. With these and other objects in view the invention consists in the novel constructions, to be hereinafter described or claimed, for carrying out the above stated objects and such other objects as hereinafter may be made to appear.

The applicant is aware that relatively superimposed and pivotally assembled buckle frame members into which a strap is threaded is old in the art, but the novelty of this invention consists in the peculiar formation of the buckle frame members and the relative securing of the side bars of both frame members by looped extremities of a third member cooperating in one position with the formation of the frame members to permit a substantial relative pivotal movement of the frame members and, in another position, to maintain the frame members in relatively gripping positions. For a clear understanding of the character of the invention, reference is made to one illustrative device embodying the novel features herein disclosed and illustrated by the accompanying draw-

ings in which the Figure 1 is an upright elevation of the device illustrating the frame members in relative gripping positions and the button loop member in a contracted condition; in Figure 2 is a side elevation of the device as illustrated in the previous figure; the Figure 3 is an elevation similar to that of the first figure, excepting that the relative positions of the buckle and button loop members is such as to permit a substantial relative pivotal movement of the frame members, the button loop being illustrated in an expanded condition; the Figure 4 is a side elevation of the device as illustrated in the next previous figure; the Figure 5 is a cross-sectional view of a flattened bar portion of the frame member upon the line "5-5" of the third figure, the Figures 6 and 7 are upright and side elevations on the part 1; the Figures 8 and 9 are upright and side elevations of the part 8; and the Figures 10 and 11 are upright and side elevations of the part 16; the Figures 12 and 13 being upright and side elevations of a modified form of the device in which a sliding intermediate bar is substituted for the button loop member.

The device as illustrated is made of three pieces of wire, one of which is bent to form the slide buckle frame member 1 illustrated by the Figures 6 and 7 of substantially rectangular from having the upper and lower bars 2 and 3, respectively, and the side bars 4 and 5 both of which have their upper portions bent backwardly, out of the general plane of the frame 1, and then gradually returned to said plane, the bend thus providing the rearwardly extending bent wire portions 6, the lower portions of the bars 4 and 5 being off-set inwardly in the plane of the frame member 1 to then be bent at right angles to form the slightly shorter lower bar 3, a substantial portion of which is flattened in the plane of the frame 1 and provided with the inwardly directed teeth 7 formed out of the flattened metal as illustrated by the figure 5. The second piece of wire is bent to form the U-shaped frame member 8 illustrated by the Figures 8 and 9 having the side bars 9 and 10 connected by the bar 11 a substantial portion of which is flattened in the plane of the frame

member 8 and provided with inwardly directed teeth $7\frac{1}{2}$ as illustrated by the Figure 3, the bar 11 being normally superimposed by the lower bar 3 of the frame member 1 as illustrated by the Figure 1. The extreme lower part of each pair of the side bars 4 and 5, and each pair of the side bars 9 and 10, are slightly bent relatively inward to compel the toothed bars 3 and 11 to engage one another while an intermediate portion of each of the side bars of one member is provided with the section 12 thereof which is divergent to an intermediate section 13 of the adjacent side bar of the other frame member. The frame member 8 is also provided with the looped extremities 14 and 15, respectively, for pivotal mounting upon the upper bar 2 of the frame member 1 so that the lower portions of the side bars 9 and 10 and the connecting bar 11 are superimposed by the lower portions of the side bars 4 and 5 and the lower bar 3 of the frame member 1, as illustrated by the Figure 1. The third piece of wire is bent to form the button loop member 16 illustrated by the Figures 10 and 11 having the axially associated button receiving loop 17 and the button retaining loop 18 with an intermediate normally contracted throat portion 19, the wire ends being bent into sections 20 and 21 in relative alignment and then bent upwardly and terminating in aligned looped extremities 22 and 23 lying in a plane at right angles to that of the button loop 16, the looped extremity 22 loosely encompassing the side bars 4 and 9, and the looped extremity 23 likewise encompassing the side bars 5 and 10 of the frame members, for sliding engagements thereon throughout their lengths, the button loop member 16 being thereby suspended substantially in the general plane of the device, but at the rear of both of the flattened bars 3 and 11. The lower portions of the pair of side bars 4 and 5 are provided with undulated surfaces 24.

In use, when the looped extremities 22 and 23 and the frame members 1 and 8 are relatively positioned as illustrated by the Figures 1 and 2, the looped extremities 22 and 23, each having passed down over the portions of undulated surfaces 24 of the pair of side bars 4 and 5 relatively divergent and then convergent with the pair of side bars 9 and 10, compel the toothed bars 3 and 11 to not only assume their relatively gripping positions, but to be maintained in such gripping positions by reasons of a portion of each of the looped extremities 22 and 23 resting within a depression of the undulated surface 24 and laterally sliding therein upon each expansion and contraction of the button loop member 16. The relative gripping positions of the toothed bars 3 and 11 are released, and the relative pivotal movements of the frame members 1 and 8 are permitted, by manually sliding the looped extremities 22 and 23 up over

the left hand side bars 4 and 9 and the right hand side bars 5 and 10, respectively, as illustrated by the Figure 3, so that, as the frame members 1 and 8 are relatively moved pivotally, the looped extremities 22 and 23 ride into their respective rearwardly extending bent wire portions 6, as illustrated by the Figures 3 and 4, and, with the frame members 1 and 8 in such a relative open position, a strap (not illustrated) may be placed between the bars 3 and 11 to be gripped thereby as the button loop member 16 is pulled downwardly to the position illustrated by the Figures 1 and 2, the teeth 7 of both of the bars 3 and 11 tending to penetrate the strap to augment the holding propensity of the gripping bars.

The Figures 12 and 13 illustrates a structure of the device identical in every detail with the preferred form excepting that the third piece of wire, instead of being bent to form a button loop, is a mere bar 25 having the looped extremities 22A and 23A identical in form and function with the looped extremities 22 and 23 of the preferred form, the bar 25 thus serving in connection with the frame members 1 and 8 as a sliding intermediate bar which is already well known to the art in connection with slide buckle frames of rectangular form.

I claim:—

1. An adjustable strap-mounting comprising wire slide buckle frame members pivotally assembled, each member having side bars connected by a gripping bar, each side bar of one member having a portion relatively divergent to a portion of the adjacent bar of the other member, and another portion of each side bar of one member being relatively convergent to another portion of the adjacent side bar of the other member, and the side bars of one member having rearwardly extending bent wire portions, and a third member provided with looped extremities slidably mounted upon the side bars of both frame members and cooperating with the rearwardly extending bent wire portions.

2. An adjustable strap-mounting comprising wire slide buckle frame members pivotally assembled, each member having side bars connected by a gripping bar, each side bar of one member having a portion relatively divergent to a portion of the adjacent side bar of the other member, and another portion of each side bar of one member being relatively convergent to another portion of the adjacent side bar of the other member, and the side bars of one member having rearwardly extending bent wire portions and lower portions having an undulated surface, and a third member provided with looped extremities slidably mounted upon the side bars of both frame members and engageable with

undulated surface, the sliding member cooperating with the rearwardly extending bent wire portions.

3. A loop slide buckle comprising wire slide buckle frame members pivotally assembled, each member having side bars connected by a gripping bar, each side bar of one member having a bent upper portion rearwardly extending, a lower portion having an undulated surface, and an intermediate portion relatively divergent to an immediate portion of the adjacent side bar of the other member, and another portion of each side bar of one member being relatively convergent to another portion of the adjacent side bar of the other member, and a third member comprising a button loop having axially associated loops with an intermediate contracted throat portion and looped extremities slidably mounted upon the side bars of both frame members and engageable with the undulated surfaces, the sliding member cooperating with the rearwardly extending bent wire portions.
4. An adjustable strap-mounting comprising wire slide buckle frame members pivotally assembled, each member having side bars connected by a gripping bar flattened in the plane of its member and provided with inwardly directed teeth, each side bar of one member having a bent upper portion rearwardly extending, a lower portion having an undulated surface, and an intermediate portion relatively divergent to an intermediate portion of the adjacent side bar of the other member, and another portion of each side bar of one member being relatively convergent to another portion of the adjacent side bar of the other member, and a third member provided with looped extremities slidably mounted upon the side bars of both frame members and engageable with the undulated surfaces, the sliding member cooperating with the rearwardly extending portions.

JESSUP SALISBURY.
